CLAIM

The ornamental design for a television receiver, as shown and described.

DESCRIPTION

1. Television receiver

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

Reproductions 1.1-1.14 show one (1) design. The subject design is characterized by a collapsible display. Reproductions 1.1-1.7 show the unused state of the subject design with the display unit collapsed and unexposed. Reproduc-

(Continued)

tions 1.8-1.14 show the use state of the subject design with the display unit fully exposed.

1 Claim, 14 Drawing Sheets
